UNITED STATES PATENT OFFICE

91,642

DESIGN FOR A RUG

Paul V. Beneville, Dumont, N. J., assignor to Bigelow Sanford Carpet Co., Inc., a corporation of Massachusetts

Application October 25, 1933, Serial No. 49,551

Term of patent 7 years

To all whom it may concern:

Be it known that I, PAUL V. BENEVILLE, a citizen of the United States, and resident of New Jersey, Bergen County, Borough of Dumont, and State of New Jersey, have invented a new, original, and ornamental Design for a Rug, of which the following is a specification:

Reference is had to the accompanying drawing, in which a plan view of the rug is shown.

I claim:

The ornamental design for a rug, substantially as shown.

PAUL V. BENEVILLE.
